UNITED STATES PATENT OFFICE.

MARJORIE BELLE ARMITAGE, OF COLORADO SPRINGS, COLORADO.

SIGNAL.

1,421,141.

Specification of Letters Patent. Patented June 27, 1922.

Application filed August 19, 1920. Serial No. 404,488.

To all whom it may concern:

Be it known that I, MARJORIE BELLE ARMITAGE, a citizen of the United States, residing at Colorado Springs, in the county of 5 El Paso and State of Colorado, have invented a new and useful Signal, of which the following is a specification.

It is the object of this invention to provide a simple means whereby the driver of 10 a motor propelled vehicle may indicate to the drivers of other vehicles, his intentions with regard to the control of the vehicle which he is driving.

The invention aims to provide a device 15 of the kind mentioned which may be mounted on a car without defacing the same, the device being adjustable to fit the car.

It is within the province of the disclosure to improve generally and to enhance the 20 utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:—

Figure 1 shows in elevation, a portion of 35 an automobile whereunto the device forming the subject matter of this application has been applied; Figure 2 is a vertical section taken approximately on the line 2—2 of Figure 1; Figure 3 is a top plan wherein parts are omitted; Figure 4 is a fragmental 40 longitudinal section showing a portion of one of the side members of the frame; and Figure 5 is a diagram illustrating the signal circuit.

The device forming the subject matter of 45 this application embodies a triangular frame, including a base 1 of hollow form, to receive and house a battery 28, the base being open at its top. The frame comprises side members, including lower tubes 2, and 50 upper tubes 3, the lower ends of the tubes 2 being secured in the base 1 adjacent to the outer edges thereof. The tubes 2 are telescoped into the tubes 3, relative longitudinal movement between the parts 2 and 3 being 55 prevented by clamping devices of any sort, such as set screws 4. The upper ends of the

tubes 3 are connected by elbows or couplings 5 to the tubes 6 and 7 of a top member, the tube 7 being slidable for adjustment in the tube 6, relative movement between the tubes 60 6 and 7 being prevented by a clamping device or set screw 8. The base 1 is adapted to be secured to the lower portion 9 of a wind shield frame 10, the top or upper member of the triangular frame being disposed adjacent to the top of the wind shield frame. The base 1 is supplied with outer seats or notches 11, located adjacent to the side members of the triangular frame, there being seats 12 in the base, located inwardly 65 70 of the seats 11, the seats 12 being deeper than the seats 11. The base has a single central seat or notch, denoted by the numeral 14.

The invention comprises an arm, including a lower member 15 telescoped for adjustment into an upper member 16, relative movement between the members 16 and 15 being prevented by a set screw 17. The member 15 is supplied with a rearwardly extended pin 18 carrying a knob 19. The pin 18 may be received in any of the seats 11, 12 or 14, the upper member 16 of the arm being received slidably in a slot 20 formed in the elements 6 and 7 which make up the top member of the triangular frame. 85

The pin 18 constitutes a fulcrum on which the arm 15—16 may be swung laterally, in the slot 20, toward and away from the inclined side members of the triangular frame. It is possible to place the pin 18 90 in any of the seats 11, 12 or 14 and, when the pin is mounted in the seats 11, the arm 15—16 being shifted accordingly, to the ends of the slot 20, an indication is given that the vehicle is about to turn to the left or to 95 the right. When the vehicle is to remain stationary, the pin 18 is received in the central seat or notch 14, the arm 15—16 being disposed in the vertical position shown in Figure 1 of the drawings. When it is desired to give no signal at all, then the pin 18 may be lowered into one of the seats 12, a flag 25 at the upper end of the part 16 of the arm being lowered accordingly.

Electric lamps 26 may be mounted on the 105 upper portion of the triangular frame, at the ends thereof, and upon the arm 6. The lamps 26 are located in a circuit including a conductor 27, the conductor 27 being housed in the hollow portions 6—7—3—2 of the triangular frame. The conductor 27 includes 110 a battery 28 housed in the base 1, the base

2
having a switch 30, interposed in the conductor 27, and constituting means whereby the lamps 26 may be lighted or turned out at will. The structure last above defined 5 constitutes means whereby a signal may be given after nightfall, when the arm 15—16 and the flag 25 cannot be seen.

Through the instrumentality of the switch 30, the lamps 26 may be lighted and 10 extinguished together, to flash signals according to any predetermined code. It is advantageous to have two of the seats 12, to the end that the pin 18 may be moved over into one of the seats 12 readily, from either 15 of the seats 11. When the arm 15—16 is swung to the left or to the right, to a position adjacent to one of the side members 2—3, the pin 18 is received in the adjacent seat 11. The arm 15—16 thus is held close 20 to the selected side member 2—3, in parallel relation thereto, and does not materially encumber the view. The upper end of the element 16 is held frictionally in the slot 20, against movement, saving under the application of an appreciable force, and the arm 15—16 will, therefore, remain in any 25 position to which it may have been swung transversely. Any suitable means may be employed for attaching the device to a vehicle, this matter being a detail well within the scope of the skill of a mechanic.

Having thus described the invention, what is claimed is:—

1. A traffic indicator comprising a frame including a base and a top bar, an arm 35 slideable on the top bar and co-operating elements carried by said arm and base permitting a lateral shifting of the arm and vertical movement thereof.

2. A traffic indicator comprising a frame 40 including a base and a top bar; an arm slideable on the top bar and provided with a projection, the base having seats receiving the projection and permitting a lateral shifting of the arm, one of the seats being deeper 45 than the other, to permit a downward movement of the arm.

3. A traffic indicator comprising a frame, a laterally movable arm provided with a projection, said frame having seats for receiving the projection and permitting a lateral shifting of the arm, one of the seats being deeper than the other to permit a 50 downward movement of the arm.

In testimony that I claim the foregoing as 55 my own, I have hereto affixed my signature in the presence of two witnesses.

Mrs. MARJORIE BELLE ARMITAGE.

Witnesses:

A. C. RANDEL,
Mrs. A. C. RANDEL.
